Primary Examiner — Selina Sikder(74) *Attorney, Agent, or Firm* — Casimir Jones S.C.;
Tyler Sisk(57) **CLAIM**

The ornamental design for a switch, as shown and described.

DESCRIPTION

FIG. 1 is a three-quarter perspective view showing our new design of a switch;

FIG. 2 is a front elevational view thereof;

FIG. 3 is a rear elevational thereof;

FIG. 4 is a left side elevational view thereof;

FIG. 5 is a right side elevational view thereof;

FIG. 6 is a top plan view thereof; and,

FIG. 7 is a bottom plan view thereof.

In the drawings, the broken lines depict portions of the switch that form no part of the claimed design.

1 Claim, 7 Drawing Sheets(56)
